UNITED STATES PATENT OFFICE.

ORRA I. FOSTER, OF HAVERHILL, MASSACHUSETTS.

SHOE.

SPECIFICATION forming part of Letters Patent No. 609,505, dated August 23, 1898.

Application filed August 13, 1897. Serial No. 648,114. (No model.)

To all whom it may concern:

Be it known that I, ORRA I. FOSTER, of Haverhill, in the county of Essex and State of Massachusetts, have invented an Improvement in Shoes, of which the following description, in connection with the accompanying drawings, is a specification, like letters on the drawings representing like parts.

In the manufacture of shoes the vamp and quarter entering into the upper are usually lined with a material different from that of the outer portion of the shoe, the said lining being joined by stitches to the material of the upper about the upper edge of the shoe. This lining is usually made of fibrous material, but in the better class of slippers it is made of thin leather; but the said lining and upper are made as separate pieces and stitched together.

I desire to facilitate the operation of making shoes and at the same time make a shoe which presents at its interior surface a material which is the same as that constituting the exterior of the shoe, the interior of the shoe presenting a face just the same as the exterior of the shoe—that is, if the shoe is made of a thin goat-skin, finished in the usual manner with a glaze, the glazing will be at the outer and also at the inner side, such shoe being easily put on and removed and presenting a very neat appearance.

Figure 1 is a side elevation of a shoe embodying my invention. Fig. 2 shows a blank constituting the quarter of the shoe represented in Fig. 1. Fig. 3 is a blank showing the vamp entering into the composition of the upper of the shoe shown in Fig. 1. Fig. 4 shows the quarter and vamp partially united as in the manufacture of the shoe. Fig. 5 shows the quarter and vamp united, each being broken out somewhat. Fig. 6 is a similar view as Fig. 5, with a different portion of the vamp broken out to show the stitches; and Fig. 7 is a section in the line xx , Fig. 6.

To make my improved shoe, I take a quarter-blank A, as shown in Fig. 2, and preferably I lay upon it two short stays B, which may be of textile material, said stays being put on the unfinished or that side of the leather or other material which is not to be exposed when the shoe is made up, and I thereafter fold the said quarter-blank cen-

trally on the dotted line aa , (shown in Fig. 2,) thus concealing the stays B. I take for the vamp of the upper a blank C, substantially of the shape shown in Fig. 3, and preferably I lay on said blank a stay C', preferably of textile material, said stay being applied at that side of the blank which is not to be exposed in the shoe—for instance, of a morocco vamp the unfinished side of the morocco. I then fold the said vamp in the dotted line c^2 . To put this quarter and vamp together, I take the extended vamp, as in Fig. 4, and apply to it the ends e' of the quarter, placing uppermost the face or finished side of the vamp which is to be exposed, and I apply to it the end e of the face or finished side of the quarter and unite the same by a line of stitches, as at e' , which stitches are extended for about half the width of the quarter at each end, and I then fold down and backwardly over the portion so stitched to the vamp the portion e^2 of the quarter, and I then stitch to the end e of the quarter and to the vamp by two lines of stitching, as at e^3 , and then the vamp is turned inwardly upon itself, leaving the upper as shown in Fig. 5. The upper is then turned wrong side out into the position Fig. 6, which conceals the stitching e^1 left at the interior of the shoe, and the upper, (shown in Fig. 6,) composed of like uniform material folded upon itself both in the quarter and vamp, is then in condition to be put upon a last in connection with a sole h , and said sole and upper will be then stitched together, making the shoe shown in Fig. 1.

Fig. 7 shows a section through the upper at the junction of the vamp and quarter on the dotted line xx , Fig. 6.

The shoe herein shown, let it be supposed, composed of a vamp and quarter of kid or morocco having a glazed face, will, when the shoe is finished, present this finished face both inside and outside just alike, and the process of applying a lining to the shoe by stitches is obviated.

The stays B receive the stitches made to unite the vamp and quarter, and the ends of the stay C' also receive the same stitches, the use of the stays materially strengthening the completed upper and shoe.

I am aware that a lumberman's sock has

been composed of two like-shaped halves of sheepskin tanned with the wool on, the seam running from the back of the leg, down the leg, under the bottom of the sole, up along 5 over the top of the foot from the toe to the top of the ankle, and then straight to the top of the leg, and that such a sock has been lined with two like-shaped pieces of felt seamed in the manner described, the top of the felt lining being sewed to the top of the sheepskin exterior.

Having fully described my invention, what I claim, and desire to secure by Letters Patent, is—

- 15 1. A shoe consisting of a vamp and quarter composed of material, each doubled centrally upon itself, so that one and the same side of said material appears at both the outer and at the inner side of the said vamp and quarter, said vamp and quarter being united together substantially as described, by stitching which is concealed when the shoe is in its finished condition, substantially as described.
- 20 2. A shoe presenting an upper composed of a seamless vamp and a seamless quarter, each of double thickness and made by folding the material of the vamp and quarter, whereby both the inside and the outside of the finished shoe present a finished face corresponding 30 exactly with the outer face of the vamp and quarter, substantially as described.
- 25 3. In a shoe, a quarter composed of material folded upon itself in the direction of the length of the quarter, the lower edge of the

folded quarter being united to the sole of the 35 shoe, substantially as described.

4. In a shoe, a vamp composed of a blank folded centrally transversely upon itself, and having its two free edges stitched or united to the sole of the boot or shoe, said folded 40 edge forming the top of the vamp and being seamless, substantially as described.

5. A boot or shoe composed of a vamp folded transversely and centrally upon itself to form a seamless double-thickness vamp, a 45 quarter folded longitudinally on itself to form a seamless double-thickness quarter, both the vamp and quarter being united together to leave a folded seamless edge of material about the upper edge of the quarter and the top of 50 the vamp, the two lower edges of each of said vamp and quarter being united with the sole of the shoe, substantially as described.

6. A shoe composed of a vamp and quarter each of double thickness to thereby constitute 55 an inner and outer face for the same, a stay applied within the folded parts of said vamp and quarter to receive the stitching used to unite said vamp and quarter, and a sole, substantially as described.

In testimony whereof I have signed my name to this specification in the presence of two subscribing witnesses.

ORRA I. FOSTER.
